UNITED STATES PATENT OFFICE.

ALONZO C. MATHER, OF CHICAGO, ILLINOIS.

DROP-BOTTOM STOCK CAR.

Application filed September 19, 1923. Serial No. 663,632.

To all whom it may concern:

Be it known that I, ALONZO C. MATHER, a citizen of the United States, and resident of Chicago, county of Cook, and State of Illinois, have invented a new and useful Drop-Bottom Stock Car, of which the following is a specification.

My invention relates to doors in stock cars which when closed form the floor of the car, and the objects of my invention are, first, to construct floor doors which are easily operated; second, to have practically the entire floor of the car formed of doors which open downward; third, to be able 15 to open and close the doors from one end of the car; fourth, to so construct the operating levers for the doors that they serve to stiffen the operating shaft; fifth, to make strong, durable and quick operating doors and other features to become apparent from the description to follow.

Since the efficiency of railroad cars is expedited by having the cars loaded in their travels across the country in both directions, I prefer to make my improved drop bottom doors in connection with stock cars, but they may be used on any other kind of car. To describe my invention so that others versed in the art to which it pertains can make and use the same, I have illustrated it on the accompanying two sheets of drawing forming a part of this specification and in which:—

Figure 1, is a bottom plan view of a car provided with my invention; Fig. 2, is a cross sectional view taken on line 2—2 of Fig. 1; Fig. 3, is a sectional view taken on line 3—3 of Fig. 2, partly broken away; Fig. 4, is a central longitudinal sectional view through one of the operating shafts partly broken away; Fig. 5, is a cross sectional view taken on line 5—5 of Fig. 4, and Fig. 6, is a cross sectional view taken on line 6—6 of Fig. 4.

Similar reference characters refer to similar parts throughout the several views.

The center sills of the car are shown at 7, the side sills at 8, the bolster at 9, the end of the car at 10 and the intermediate braces at 11, which parts are of the usual construction in cars. The floor 12, see Fig. 2, above the center sills 7 and also above the bolster 9 and braces 11 necessarily has to be fixed but the balance of the floor of the car comprising sixteen rectangular shaped sections is made in the form of

hinged doors 13 connected to the center sills by the hinges 14 and arranged to swing down to an angle of about 40 degrees.

The mechanism designed for rigidly holding the sixteen doors in a closed position level with the floor of the car and sufficiently strong to support dead weight or live weight as cattle, comprises a shaft 15 preferably square in cross section extending the entire length of the car under each row of eight doors 13 on each side of the car, said shaft having its bearings in suitable boxes 16 supported beneath the car on hangers secured to the bolsters 9, the end 70 sills 10 and the braces 11. Mounted on the shaft to turn with the same underneath each door 13 are two lifting arms 17 provided with anti-friction grooved rollers 18 on their free ends to engage suitable tracks 75 19 secured to the doors 13. The arms 17 are so positioned and are of such length with respect to the position of shaft 15 that the doors 13 will be in a horizontal position 80 when the arms 17 are in their upper or vertical position, and the doors 13 will be in their lowermost position as shown by dotted lines in Fig. 2, when the arms 17 are in their lowered position. Obviously the arms 17 on one side of the car are operated in unison by their cooperating shaft 15.

The mechanism provided for turning or operating the shaft 15 comprises a large gear wheel 20 mounted on one end of the shaft 15 to turn therewith which meshes with a pinion 21 rigidly mounted on a shaft which has its bearing 22 secured to the end sill 10 and is provided on its exposed end with the operating crank 23, and the ratchet wheel 24 which is engaged by the pawl 25 pivotally mounted on the end of the car. The pawl and ratchet are so arranged that the shaft 15 will be locked against rotation when the doors are closed and to drop the doors the pawl 25 must be lifted out of engagement with the ratchet wheel 24. To make a strong and rigid construction I prefer to have the rollers 18 on the free ends of the arms 17 pass the dead center above the shaft 15 when the doors 13 are closed and to prevent the same from moving too far beyond the dead center I provide the stops 26 on the tracks 19. The tracks 19 are extended out beyond the stops 26 to serve as lower braces for the door 13. The square shaft 15 is provided with bearing sleeves 27 within the boxes 16.

While the shaft 15 may be made sufficiently heavy to prevent its twisting when lifting the doors to a closed position, I prefer to form integral interlocking tapered 5 lugs 29 on the meeting ends of the sleeves on said shafts as well as on the hubs of the gear wheels 20, and applying a screw nut 28 on each end of the shaft 15 to draw the parts mounted on the shaft tightly together and forming a rigid cast sleeve on the exterior of the shaft. In such case of course the shaft may be round instead of square in cross section. It will be understood that the arms 17 are provided with 10 sleeves 30 at their pivotal ends.

In operation to lower the doors the pawl 25 is lifted out of engagement with the ratchet wheel 24 and the crank 23 is turned clockwise as viewed in Fig. 2, and to raise 20 the doors the pawl 25 is permitted to engage the ratchet wheel 24 by gravity and the crank 23 is turned counter-clockwise as viewed in Fig. 2.

It will be understood that the size, form 25 and arrangement of the parts may be changed without in the least departing from the scope of my invention.

Having thus fully described my invention what I claim as new and desire to 30 secure by Letters Patent of the United States is:—

1. In a device of the class described, floor doors hinged to the car frame, a compound shaft arranged below the free ends of the 35 doors comprising a plurality of sleeves locked together to turn in unison and a center rod, arms mounted on said shaft to turn therewith and to have their free ends engage the lower sides of the doors and 40 means for rotating said shaft to raise and lower the doors.

2. In a device of the class described; floor doors; a built-up shaft comprising a 45 sleeve forming the hub of a gear, a sleeve forming the fulcrum of an arm arranged to

have its free end engage one of said doors and a rod to hold the sleeves in alignment.

3. In a device of the class described, floor doors, a built-up shaft, arms to operably connect the shaft and the doors, bearing boxes for the shaft and a gear to rotate said shaft, said shaft comprising a hub of the gear and sleeves forming the pivotal ends of said arms and a center rod to hold the parts in alignment. 50

4. In a device of the class described, floor doors, a built-up shaft, arms to operably connect the shaft and the doors, bearing boxes for the shaft and a gear to rotate said shaft, said shaft comprising sleeves forming the pivotal ends of said arms and a center rod provided with end nuts to clamp the shaft endwise. 55

5. In a device of the class described, floor doors hinged at the center of the car, a compound shaft arranged below the free ends of the doors comprising a plurality of sleeves having inter-locking lugs on their meeting ends and a center rod provided with nuts at each end to clamp the sleeves together, arms mounted on said shaft to turn therewith and to have their free ends engage the lower side of the doors and means for rotating said shaft to raise and lower the doors. 60

6. In a device of the class described, floor doors; a built-up shaft; arms to operably connect the shaft and the doors; bearing boxes for the shaft and a gear to rotate said shaft; said shaft comprising bearing sleeves within the boxes, a hub of the gear, and sleeves forming the pivotal ends of said arms and a center rod provided with end nuts to clamp the shaft endwise, said gear hub and said sleeves having interlocking lugs. 65

In testimony whereof I have signed my name of this specification this 7th day of September, 1923, at Chicago, Illinois.

ALONZO C. MATHER.
